HEATING PAD

Ronald Lyman McFarlan, Marblehead Neck, and
John A. C. Bowles, Boston, Mass.

Application December 18, 1936, Serial No. 116,514

11 Claims. (Cl. 219—46)

This invention relates to heating pads, and with regard to certain more specific features, to electric heating pads such as are used in homes and hospitals.

5 Among the several objects of the invention may be noted the provision of a heating pad of the class described which includes an electric or other heating element for supplying heat energy to the pad, and a heat storing or thermophoric composition for delivering up said heat energy as supplied to the pad, over a protracted period of time; the provision of a heating pad of the class described which is provided with means automatically regulating the temperature to be achieved 10 by the pad; the provision of a heating pad of the class described which is substantially hermetically sealed, and which is capable of extended use and re-use over long periods of time without any substantial deterioration; the provision, in a 15 heating pad of the class described, of a new thermophoric composition of matter, which is adapted to deliver up heat stored therein (such as latent heat of fusion) over a greatly protracted period of time, which composition of matter undergoes a reversible reaction on the introduction 20 and withdrawal of heat thereto and therefrom, without substantially changing any compositional characteristics over repeated reversals; and the provision of a heating pad, and a thermophoric composition of matter for use therein, which are economical in construction and operation. Other objects will be in part obvious and in part 25 pointed out hereinafter.

The invention accordingly comprises the elements and combinations of elements, features of construction and composition, and arrangements of parts, which will be exemplified in the structures and products hereinafter described, and the scope of the application of which will be indicated 30 in the following claims.

In the accompanying drawing, in which is illustrated one of various possible embodiments of the invention,

Fig. 1 is a plan view of a heating pad embodying the present invention;

Fig. 2 is a cross section taken substantially along the line 2—2 of Fig. 1;

Fig. 3 is a cross section taken substantially along line 2—2 of Fig. 1;

Fig. 4 is an enlarged cross section taken substantially along line 4—4 of Fig. 1; and,

Fig. 5 is a cross section taken substantially along line 5—5 of Fig. 4.

Similar reference characters indicate corre-

sponding parts throughout the several views of the drawing.

Referring now more particularly to Fig. 1, numeral 1 indicates a rubber or like flexible, plastic material bag or sack, which is shown as of generally rectangular shape. The shape of the bag 1 is of no importance, however. At one end thereof, the bag 1 is formed as a neck or cylindrical outlet portion 3. In the finished pad, the preferred form of the outlet 3 is a solid cylindrical 10 member which embeds a pair of electrical connecting prongs 5 which are adapted to be inserted into the customary form of electric outlet. However, it is contemplated that the prongs 5 may be replaced by other connecting means, such 15 as suitable socket elements, so that electrical connections may be made to the pad by fitting in a plug rather than by plugging the device itself into a socket.

Inside the bag 1 there is provided an electrical 20 heating device indicated generally by numeral 7. In the preferred embodiment of the invention, the device 7 comprises an electrical resistance heating coil 9 embedded in a flexible rubber or like matrix 11. The construction of this device 25 7 may well be of the type shown in DeLaney et al. Patent 2,018,512, dated October 22, 1935. Included in the device 7 is a thermostat 13, likewise embedded in the matrix 11. The construction of the thermostat 13, which is likewise shown 30 in the aforementioned DeLaney et al. patent, is indicated for convenience in Figures 4 and 5. It comprises a box 15 having a cover 17. Mounted in one end of the box 15 in such manner as to project into the central hollow portion of the 35 box 15 is a bimetallic blade 19. The resistance heating coil 9 is connected to one end of the blade 19 by a connection indicated by numeral 21. The other end of the blade 19 carries a movable contact 23, which cooperates with a fixed 40 contact 25 mounted in the box 15, which is in turn connected, exteriorly of the box 15, with another portion of the resistance heating coil 9. The resistance heating coil 9 has its opposite 45 ends connected to the two prongs 5, with the thermostat 13 in series therewith.

The leads of the resistance heating coil 9, indicated by numeral 26 in Fig. 1, are embedded in a neck 27 of rubber or like material which serves 50 structurally to interconnect the device 7 and the plug portion 3 of the outer bag 1. In the preferred embodiment of the invention, the neck 27 connects to the solid portion of the plug 3 in such manner as to leave an annular trough or 55

declivity 29 therebetween, the purpose of which will be explained hereinafter.

In the preferred embodiment of the invention, all rubber parts heretofore mentioned, including the bag 1, the cylindrical portion 3, the matrix 11 of the device 7, and the neck 27, are vulcanized or fused together in such manner as to form a homogeneous, hermetically sealed unit. The final sealing is not ordinarily done, however, until after a certain thermophoric composition to be described, has been placed in the bag.

From Figures 1 and 2, it will be noted that the heating device 7 hangs rather loosely in the bag 1, by means of the neck 27, in such manner as to provide a relatively large free space 31 therein. The free space 31 is filled, in the finished article, with a thermophoric composition. A preferred thermophoric composition is as follows:

	Percent by weight
20 Manganous chloride tetrahydrate (MnCl ₂ .4H ₂ O)	3.45
25 Sodium acetate trihydrate (NaC ₂ H ₃ O ₂ .3H ₂ O)	96.55
25 An alternative thermophoric composition, likewise found to be satisfactory, is as follows:	

	Percent
30 Manganous chloride tetrahydrate (MnCl ₂ .4H ₂ O)	3.3
35 Sodium acetate trihydrate (NaC ₂ H ₃ O ₂ .3H ₂ O)	93.7
35 Glycerine	3.0

Still another satisfactory thermophoric composition is as follows:

	Percent
40 Manganous chloride tetrahydrate (MnCl ₂ .4H ₂ O)	3.3
45 Sodium acetate trihydrate (NaC ₂ H ₃ O ₂ .3H ₂ O)	94.0
50 Ethylene glycol (CH ₂ OH.CH ₂ OH)	2.7

If different temperatures of operation are desired, the proportions in the above compositions may be varied without disturbing the desired action of the compositions.

In general, the space 31 is completely filled with one of the thermophoric compositions above described, or any other suitable thermophoric composition, and the bag then finally hermetically sealed.

The operation of the heating pad as thus described is as follows:

The pad is connected by the prongs 5 to a source of electric current, whereupon the heating device 7 commences to deliver heat, and the electrically generated heat is stored by the conversion of the sodium acetate in the thermophoric composition from its crystalline form to its liquid form. The thermostat 13 shuts off the electric current after the crystalline mixture has been substantially converted into liquid form. Normally, the thermostat 13 should be set to open the circuit upon the attainment of a temperature not greatly in excess of 75° C. in the pad, because temperatures in excess of this value are sometimes destructive to the thermophoric compositions above specified.

The heating pad may now be disconnected from the electric source and carried to the location of its desired use. As the sodium acetate mixture slowly recrystallizes, its latent heat of fusion is released, and this latent heat suffices to keep the pad hot for many hours.

The manganous chloride is introduced into the thermophoric composition because of its property

of changing from the tetrahydrate to the dihydrate form at a temperature of the order of 58° C., which is approximately the same temperature at which sodium acetate loses its water of crystallization. When the melted mixture is cooling, and giving off heat, the change from manganous chloride dihydrate to manganous chloride tetrahydrate removes water from the melt, thus tending to prevent supersaturation of the melt and consequent failure of the sodium acetate to re-crystallize.

The annular trough 29 hereinbefore mentioned likewise aids in preventing supersaturation and failure of recrystallization, because it is so formed as to contain a certain amount of the thermophoric composition which, through being removed a greater distance from the heating unit 7, usually does not melt during the controlled time interval for the melting of the rest of the thermophoric composition. When cooling commences, the presence of a small amount of solid thermophoric composition in the annular trough 29 serves to seed the crystallization of the liquid portion of the thermophoric composition, and thus tends to inhibit the formation of supersaturated solutions. Obviously, for this purpose, the trough 29 may be replaced by any other suitable recess, within the scope of the invention.

In preparing the thermophoric composition, care should be exercised not to expose it to the air for too long a time, such as more than six hours, because there is a tendency for the manganous chloride to form manganese hydroxide upon extended exposure to the air.

In operation, the pad should be allowed to come to room temperature before reheating.

Depending upon the size of the pad, the time required for heating it is from the order of ten to the order of fifteen minutes, and the time during which the pad will stay hot will vary from the order of ten to the order of twenty hours. The pad automatically maintains a temperature in the region of 58° C. for the thermophoric mixtures above given. This temperature can be varied somewhat by varying the proportions of the constituents in the thermophoric composition. The figure of ten to twenty hours (during which the pad will stay hot) has been experimentally ascertained and found to hold true for an eight hundred gram quantity of the thermophoric composition.

While in the foregoing description details have been given for the mechanical structure of a preferred embodiment of the invention, it will readily be seen that the mechanical form of the invention may be widely varied without departing from the spirit of the invention.

Nor is the above description to be considered as limiting the invention to the particular thermophoric composition described, as many other suitable compositions may be satisfactorily used in the general combination, either to achieve different temperatures, during the prolonged cooling period, or for other reasons. However, it is to be noted that the thermophoric compositions herein described, which are believed to be novel with the present invention, are particularly advantageous for use in connection with the heating pad of the present invention, because of their characteristics hereinbefore given, and because they are capable of sustaining a temperature that so nearly approximates the desired temperature for a heating pad of the general character here concerned.

An incidental advantage of the heating pad

shown in the present invention is that it can be heated by means other than the electric current. For example, the pad shown in Fig. 1, in the event of non-availability of electric current, may be heated simply by dropping it into a pan of boiling water for a sufficient length of time to bring substantially all of the thermophoric mixture to a liquid condition (this can readily be ascertained by feeling the bag and noting its relative rigidity as the heating progresses). Thereafter, the bag can be removed from the hot water and it will give off heat over a protracted period of time in much the same manner as if it had been heated electrically.

15 By making pads of associated elements of rubber, a flexibility is provided which is distinctly advantageous in pads of this type, since it permits the pad to conform to the part of the body with which it is placed in contact. However, 20 such flexibility is sometimes not necessary, and in that event, it is within the scope of the present invention to make the pad out of metal, fiber, or any other suitable container material.

The thermophoric compositions herein set forth are separately claimed in our copending application Serial No. 173,220, filed November 6, 1937.

In view of the above, it will be seen that the several objects of the invention are achieved 30 and other advantageous results attained.

As many changes could be made in carrying out the above constructions and compositions without departing from the scope of the invention, it is intended that all matter contained in 35 the above description or shown in the accompanying drawing shall be interpreted as illustrative and not in a limiting sense.

We claim:

1. In a heating pad, a container, a thermophoric composition within said container, and electrical resistance means within the container for supplying heat to said thermophoric composition, said container comprising a bag made of a flexible material.

45 2. In a heating pad, a container, a thermophoric composition within said container, and means within the container for supplying heat to said thermophoric composition, said container comprising a bag made of a flexible material, 50 said heating means comprising an electrical resistance heating unit embedded in a flexible matrix.

3. In a heating pad, a container, a thermophoric composition within said container, and 55 means within the container for supplying heat to said thermophoric composition, said container comprising a bag made of a flexible material, said heating means comprising an electrical resistance heating unit embedded in a flexible matrix, said bag being hermetically sealed about the thermophoric composition.

4. In a heating pad, a container, a thermophoric composition within said container, means 60 within the container for supplying heat to said thermophoric composition, said means comprising an electrical resistance heating element, and

a thermostat in the container in series with said electrical resistance heating element, said thermostat being adapted to disconnect the element from a source of electricity when the temperature of the pad reaches a predetermined value. 5

5. In a heating pad, a container, a thermophoric composition within said container, and means within the container for supplying heat to said thermophoric composition, said container having an interior recess at a point relatively 10 remote from the heating means, the said recess being adapted to contain a portion of said thermophoric composition and substantially maintain it against melting while the remainder of the thermophoric composition is melting under 15 the heating influence of said heating means.

6. In a heating pad, a container, a thermophoric composition within said container, means within the container for supplying heat to said thermophoric composition, said means comprising an electrical resistance heating element, and a thermostat in the container in series with said electrical resistance heating element, said thermostat being adapted to disconnect the element from a source of electricity when the temperature of the pad reaches a predetermined value, 20 said container having an interior recess at a point relatively remote from the heating means, the said recess being adapted to contain a portion of said thermophoric composition and substantially 25 maintain it against melting while the remainder of the thermophoric composition is melting under the heating influence of said heating means.

7. A heating pad as set forth in claim 5, in 35 which the container comprises a rubber sack.

8. A heating pad as set forth in claim 6, in which the container comprises a rubber sack.

9. In a heating pad, a container, a thermophoric composition within said container, and 40 means within the container for supplying heat to said thermophoric composition, said thermophoric composition comprising a mixture of sodium acetate trihydrate and manganous chloride tetrahydrate. 45

10. In a heating pad, a container, a thermophoric composition within said container, and means within the container for supplying heat to said thermophoric composition, said thermophoric composition comprising a mixture of sodium acetate trihydrate and manganous chloride tetrahydrate, the sodium acetate trihydrate 50 constituting more than the order of 90% of the mixture.

11. In a heating pad, a container, a thermophoric composition within said container, and means within the container for supplying heat to said thermophoric composition, said thermophoric composition comprising a mixture of sodium acetate trihydrate and manganous chloride tetrahydrate, together with a small proportion 55 of a liquid selected from the class composed of glycerine and ethylene glycol.
